UNITED STATES PATENT OFFICE.

CHARLES E. CATHER, OF WORCESTER, AND ROBERT C. BOOTH, OF HOLDEN, MASSACHUSETTS, ASSIGNEES TO UNITED STATES ENVELOPE COMPANY, OF SPRINGFIELD, MASSACHUSETTS, A CORPORATION OF MAINE.

ENVELOP.

1,185,767.

Specification of Letters Patent. Patented June 6, 1916.

Application filed August 30, 1913. Serial No. 787,531.

To all whom it may concern:

Be it known that we, CHARLES E. CATHER and ROBERT C. BOOTH, both citizens of the United States, residing at Worcester and Holden, respectively, in the county of Worcester and Commonwealth of Massachusetts, have jointly invented a new and useful Improvement in Envelops, of which the following is a specification, accompanied by 10 drawings forming a part of the same.

Our present invention relates to an improvement in that class of envelops designed to contain merchandise and be transmitted through the mails.

15 It consists in the construction and arrangement of parts as hereinafter described and pointed out in the annexed claims.

The object of our invention is to avoid the difficulty of applying stamps, post marks, or 20 written matter to the body portion of an envelop when the same is expanded by its contents into an irregularly shaped parcel.

Referring to the accompanying drawings, Figure 1 represents an elevation of our improved envelop. Fig. 2 is a sectional longitudinal cross section. Fig. 3 represents the envelop blank in its expanded form and provided with adhesive material preparatory to the completion of the envelop by folding.

30 Similar reference letters and figures refer to similar parts in the different views.

Referring to the drawings 1 denotes the body portion of an envelop formed from a blank 2, represented in its flat or expanded 35 form in Fig. 3.

3 denotes the seal flap, 4 the back flap, and 5, 6, two flaps upon each side of the body portion which are folded upon the body portion with their overlapping edges attached.

40 In preparing the blank represented in Fig. 3 for the operation of folding, gum is applied to the back flap 4, to the seal flap 3 upon its shaded portion 7, to the shaded portion 8 of the flap 6, and also in a narrow 45 band extending transversely across the blank, as represented at 9, Fig. 3. The gummed blank, as represented in Fig. 3, is then folded upon the lines 10, 11 and 12, and in the order named. The flap 5 is thus 50 folded upon the body portion of the envelop. The flap 6 is next folded upon the body portion of the envelop with the gummed surface 8 overlapping the edge of the flap 5, and finally the back flap 4 is

folded upon and attached to the outer surfaces of the flaps 5 and 6, as represented in Fig. 1. The operation of folding the flap 5 upon the body portion of the envelop causes it to adhere to the body portion of the envelop by means of the strip of gum 9, and in like manner the flap 6 when folded upon the body portion of the envelop is caused to adhere by reason of the strip of gum 9. The adhesion of the flaps 5 and 6 to the body portion of the envelop by means 55 of the gummed surface 9 securely closes the envelop upon the plane of the gummed surface 9, preventing the contents placed in the envelop from passing into the space between the gummed surface 9 and the end of the envelop which is closed by the back flap 4. The insertion of the merchandise is apt to bulge the envelop, making it inconvenient to write the address thereon, to affix stamps thereto, or to post mark the package. This 60 difficulty is entirely obviated by our present improvement, as that portion of the envelop between the gummed surface 9 and the end closed by the back flap remains flat, allowing the address to be written thereon, stamps 65 applied thereto, or a post mark affixed.

We are aware that the body portion of the envelop may be closed between its ends otherwise than by the application of a gummed strip 9. We are also aware that it 70 has been proposed to provide an envelop with an extension to receive an address, and we do not claim such broadly. The essential feature of our invention, however, inheres in the forming of a second or supplemental bottom to the space within the envelop in which the merchandise is contained, for the purpose of leaving one end of the envelop flat and not distorted by the insertion of its contents, and providing a space 75 between the gummed strip 9 and the gummed back flap 4, which consists of a double thickness of ungummed paper, upon which the address may be written and the mailing stamp affixed and canceled.

100 We claim,

1. As a new article of manufacture, a merchandise envelop having front and rear walls, a seal flap at one end, and a bottom flap at the other end permanently uniting said front and rear walls, said front and rear walls being permanently united transversely at a distance removed from said

closed bottom flap to provide a bottom for the merchandise pocket of the envelop, whereby an ungummed section is provided between said bottom flap and said bottom.

5. 2. As a new article of manufacture, a merchandise envelop formed from a blank having a body portion forming a front wall and having side flaps folded upon said body portion to form a rear wall, a bottom flap 10 folded upon said side flaps and attached thereto, to permanently unite said front and rear walls, said front and rear walls being permanently united transversely at a distance removed from said bottom flap to provide a bottom for the merchandise pocket of 15 the envelop.

3. A merchandise envelop having one end open and having its opposite end closed by

a narrow flap of substantially uniform width, and means for uniting the front and back of the envelop on a line contiguous to and parallel with said narrow closing flap, whereby an ungummed section of uniform width is provided between said narrow closing flap and said united portions. 20

Signed this sixteenth day of August, 1913.
